UNITED STATES PATENT OFFICE.

EDWARD F. PARKS, OF PROVIDENCE, RHODE ISLAND, ASSIGNOR TO UNIVERSAL
WINDING COMPANY, OF BOSTON, MASSACHUSETTS, A CORPORATION OF
MASSACHUSETTS.

WINDING-MACHINE.

1,326,088.

Specification of Letters Patent. Patented Dec. 23, 1919.

Application filed April 7, 1917. Serial No. 160,513.

To all whom it may concern:

Be it known that I, EDWARD F. PARKS, a citizen of the United States, residing at Providence, in the county of Providence, 5 State of Rhode Island, have invented certain new and useful Improvements in Winding-Machines, of which the following is a specification.

My invention relates to winding machines and consists of improvements in the starting- and stopping-mechanism therefor. My improvements are directed particularly to that type of machine known as friction-drive or drum-winders in which the cop or 15 package is rotated through frictional contact of its surface with a driving-roll or drum. The object of the invention is to provide a quick-acting, positively-operated means for removing the cop from driving 20 contact with the drive-roll, and for releasing the yarn from the traversing thread-guide when it is desired to stop the winding. Other objects of the improvement are to provide means for controlling the movement 25 of the winding-spindle or mandrel as it recedes from the drive-roll during the growth of the package; to apply a braking force to the mandrel to insure quick arrestment of its rotation; to hold the mandrel in its raised position upon the stopping 30 of the machine; and to otherwise facilitate and render more convenient the whole operation of the machine.

The manner and means for carrying out 35 the improvements are fully explained in the following specification, illustrated by the accompanying drawings, in which like reference characters designate like parts. In the drawings:—

40 Figure 1 is a general, plan view of my improved winding machine;

Fig. 2, an enlarged, side view of the same, part sectional on the line X—X of Fig. 1, and showing the end cover of the machine-frame or casing removed to disclose 45 the traverse-cam and its driving-connections;

Fig. 3, an enlarged, detail view of the drive-roll, winding-mandrel and thread-guide in end elevation, showing the stopping-mechanism for the mandrel and the yarn-releasing means for the thread-guide;

Fig. 4, a sectional, detail view of the spindle dogging-device;

55 Fig. 5, a detail view of the yarn-releasing

means or thread-bail shown in relation to the thread-guide; and

Fig. 6, a plan view of the tension-devices and correlated end-stop mechanism of the machine.

60

My improvements are herein shown as applied to a machine of the same general construction as that described and illustrated in my copending application, Serial No. 105,425, filed June 23, 1916. Referring particularly to Figs. 1 and 2, the essential elements of the winding-mechanism are mounted on a box-like casing or frame F and comprise the winding-mandrel B, the drive-roll D, the thread-guide G and the traverse-cam C. Journaled in bearings at the sides of the frame F is a horizontal shaft S on which the cam C is fixedly mounted and at one end whereof is a friction drive-wheel W. Mounted in a movable bracket or standard E at the rear of the machine is a stud-shaft h, carrying a belt-pulley H at one end, and at its opposite end is a friction-disk K arranged with its face engaging the periphery of the cam-driving wheel W. The pulley H is connected by a belt to the main drive-shaft of the machine, usually arranged below, but not here shown, and generally extending the whole length of a frame or bed upon which a plurality of units or winding-heads are supported. As the pulley H is rotated from the main drive-shaft its shaft h rotates the disk K, which, in turn, drives the wheel W through frictional contact therewith. By adjusting the position of the bracket E to shift the disk K across the rim of the wheel W the speed-ratio between the drive shaft and cam C may be regulated in the usual manner as well known in the art. The speed-changing device for the cam C is operated through the movement of the winding-mandrel B away from the drive-roll D as the winding increases in diameter to alter the speed of traverse of the thread-guide whereby to regulate the laying of the yarn-coils in accordance with the change in speed of rotation of the cop. The purpose and method of operation of this part of the winding-mechanism is described in detail in my copending application before referred to and therefore will not be further explained herein.

100
105
110

The drive-roll D is rotatably mounted on the forward end of the frame F, above the cam C, by means of a shaft D' jour-

naled in the side-bearings d , d , see Figs. 1 and 2. Referring particularly to Fig. 1, the drive-roll shaft D' carries a pulley P at one end which is belted to a pulley on the main drive-shaft of the machine, or, if preferred, the two shafts might be connected by gearing. Below the roll D are two parallel, horizontal rods r , r' extending across the interior of the frame F and supported at their ends in the bearings f , f' , see Fig. 2. Mounted on the upper rod r is a traverse-slide L which carries the thread-guide G . Preferably the slide L is constructed in the form of a tubular bushing or quill to which is secured a sheet-metal member L' having the guide G made integral therewith. The member L' comprises two spaced arms l , l' surrounding the bushing L , as shown in Fig. 5, and the connecting portion between the arms is extended upwardly in the curved guide-member G . Reaching out from the side of the member L' is another arm l' bent into a hook at its end, see Fig. 2, to adapt it to inclose the lower guide-rod r' . Projecting from the bottom of the member L' is a pin or stud o on which is journaled a roll O adapted to engage with the helical groove c in the periphery of the cam C in accordance with the usual arrangement. The guide-arm G is curved to adapt it to lie close to the periphery of the drive-roll D , as shown in Fig. 2, and at its top is an enlargement g bent into a vertical plane and formed with a thread-slot g' , see Fig. 5. The top of the guide G is thus arranged to lie close to the point of contact of the cop with the drive-roll D and is maintained in this relation by the arm l' which embraces the rod r' . As the cam C is rotated the engagement of its groove c with the roll O will cause the slide L to be reciprocated along the rods r , r' and the guide G will thus be traversed longitudinally of the axis of the winding-mandrel B .

As shown in Fig. 1, the winding-mandrel B is constructed in the form of a tube or cylinder, generally made from wood, and having a cross-slot b at one end. The bore b' of the mandrel or cop-tube B is adapted to receive the ends of two opposite "live" spindles V , V' journaled in bearings t , t' at the ends of the side-arms T , T' of a swinging frame U . The right-hand spindle V carries a collar or flange v on the face of which is a spline or key v' adapted to engage the cross-slot b in the end of the tube B to connect it rotatively therewith. The spindle V also carries a brake-wheel or disk M through which the rotation of the tube or mandrel B is arrested in the manner and for the purpose as later described.

The frame U in which the mandrel-supporting spindles V , V' are journaled is of substantially rectangular shape with its

arms T , T' connected by the cross-members 2 and 3. At its rearward end the frame U is pivoted on a cross-rod u held in bearings f , f' on the frame F . The bearing for the left-hand mandrel-spindle V' is formed at the end of an auxiliary arm or hand-lever J pivoted at j to the side of the main arm T' . A spring j' serves to maintain the arm J normally in the position illustrated in Fig. 1 to hold the spindle V' in engagement with the bore of the tube B , but when it is desired to remove the mandrel the arm may be swung to one side against the action of the spring.

Pivoted on the rod u which supports the frame U at the rear of the main frame F is a brake-arm or lever N which also serves as the main instrumentality for raising the winding-mandrel B away from the drive-roll D to arrest its rotation. The lever N extends along the inner side of the arm T of the frame U as shown in Fig. 1, and at its outer end is formed with an arched portion N' . At the extremity of the arch N' is a brake-shoe n adapted to engage with the periphery of the brake-disk M on the spindle V , see Figs. 2 and 3. Straddling the sides of the portion N' of the lever N is an arm Q which is pivoted on a pin q driven through the lever. Pivoted on a stud z projecting from the side of the arm T of the frame U is a finger-lever Z having an arm z' reaching out toward the front of the machine and overlying a finger-hold extension Z' on the arm T . The opposite arm 4 of the lever Z is of triangular shape and is pivotally connected to the lower end of the arm Q by a stud or pin 5. A relatively strong spring I is secured to the lower end of the lever Z and anchored at i to the extension Z' on the arm T . The tendency of the spring I is to rock the lever Z in the direction opposite to that indicated by the arrow x' , Fig. 3, to raise the frame U in relation to the lever N to carry the brake-disk M against the shoe n , the arm Q acting as a toggle-link for this purpose, as more fully explained hereinafter. The lever Z also serves as a means for controlling the braking-device manually and by pressing its extension z' toward the finger-piece Z' on the arm T it may be rocked to move the brake-disk M away from the brake-shoe n in the manner and for the purpose as later explained. As shown in Fig. 3, the arm 4 of the lever Z is formed with a substantially sector-like portion 6 having detent-notches 7 and 8 in its edge adapted to be engaged by the pointed end 9 of a push-rod 10 to hold it in different positions, whereby to regulate the coaction between the brake-lever N and the frame U . The rod 10 is mounted to slide in a lug 11 projecting from the side of the arm T of the frame U and at its rearward end is bent at right-angles 130

and hooked through the end of one arm 12 of a bell-crank-lever 13. The lever 13 is pivoted on a stud 14 screwed into an extension on the top of the brake-arm N and its 5 opposite arm 15 is pivotally connected to the end of a link or slide-bar 16 by means of the screw 17.

The opposite end of the side-bar 16 is supported on a pin 18 driven into the side 10 of the cover of the main frame F and projecting through a substantially V-shaped cam-slot 19 in the bar. The forward end of the bar 16 is formed with a fork 20 having a slot 21 through which it is connected to 15 operate the yarn-releasing bail for the thread-guide in a manner as later explained. The bar 16 also carries a knock-off lever 22 at its outer end, preferably constructed of sheet-metal in channel form to adapt its 20 sides to receive a pivot-pin 23 extending through the bar. At its rearward end the bottom section of the channel is cut away at 24, see Fig. 3, to provide a cross-bar 25 which is adapted to be engaged by the teeth 25 of a ratchet-wheel 26 attached to the hub of the cam-shaft drive-wheel W. Two fingers or prongs 22^a project upwardly from this end of the lever 22 and straddle the bar 16 to guide the lever in its movement in relation thereto. The knock-off lever 22 is rocked to engage its end 25 with the ratchet-wheel 26 through the connection of its forward end with the end-stop or drop-wire devices of the machine to be later described. Suffice it for the present to state that when 35 it is carried into engagement with the ratchet-wheel 26 it will be moved thereby in the direction indicated by the arrow x, Fig. 3, to slide the bar 16 in the same direction. This action serves to rock the lever 13 to withdraw the detent-rod 10 from engagement with the notches in the sector 6 of the lever Z whereby to allow the latter to act 40 in a manner as later explained.

The bell-crank-lever 13 is controlled by a spring 27 to maintain the detent-rod 10 normally engaged with the notch 7 in the lever Z during the operation of the machine, as illustrated in Fig. 2. One end of the 45 spring 27 is hooked through a hole in the arm 12 of the lever 13 and its opposite end is similarly secured to the end of a lever 28. The lever 28 is fast on a rod 29 pivoted in bearings projecting from the under side 50 of the brake-lever N, see Fig. 3. The inner end of the rod 29 is bent at right-angles to its pivot portion, see Fig. 1, and extends in the crooked arm 30. As shown in Figs. 3 and 4 the opposite sides of the arm 30 are 55 milled off to provide a wedge-shaped cross-section which is adapted to engage the tapered groove 31 of an arcuate-shaped track or quadrant 32. The quadrant 32 is secured to the main frame of the machine at 33, and 60 65 34, see Fig. 2, and is formed concentric

with the axis of the rod u on which the frame U and arm N are pivoted. Therefore, as these two members swing upwardly the arm 30 of the rod 29 will slide freely in the groove 31 of the track 32, but on the contrary, the downward movement of the frame and lever will be resisted by the binding action of the arm in the groove. This dogging effect results from the tendency of the arm 30 to rock under the action 70 of the spring-pressed lever 28 in accordance with a familiar principle as usually employed in the winding-machine art. The lever 28 is formed with a toe-portion 35 extending forwardly from the rod 29 into position 75 beneath the lower end of the lever Z. The end of the toe 35 is beveled off at 37 to adapt it to be engaged by a latch-member 38 carried on the pivot-pin 5 of the lever Z, and also by a rounded lug 39 on the lower end 80 of the lever, see Figs. 2 and 3. The latch 38 is preferably constructed of sheet-metal with two ears 40 straddling the end of the lower arm 4 of the lever Z and encircling the pin 5 on either side thereof. Connecting 85 the ears 40 is a strip-like piece 41 folded on itself at 42 and then bent out at right-angles in the finger 43 which bears against the side of the lever Z to act as a stop, see Fig. 3. The upper portion of the strip-piece 41 extends in an angularly-bent arm 44 which serves as a counterweight to maintain the latch normally in the position shown in Figs. 2 and 3 with its stop 43 against the lever 90 Z. With the parts in the position as shown 95 in Fig. 3, when the arm z' of the lever Z is pressed downwardly to rock its arm 4 in the direction indicated by the arrow x', the lower end of the latch 38 will wipe across the beveled end 37 of the toe 35 of the lever 100 28. The latch 38 is thus caused to act as a wedge to depress the toe-portion 35 of the lever 28 whereby to turn its rod 29 to rock its dog-arm 30 downwardly. This action 105 releases the dog 30 from its binding engagement in the groove 31 of the quadrant 32, but as soon as the latch 38 rides over the bevel 37 on the toe 35 the lever 28 is free 110 to move again under the action of the spring 27. During the first part of the movement 115 of the hand-lever Z the upper notch 8 comes into engagement with the detent-rod 10, but at this juncture the latch 38 will not have been carried far enough to engage the toe 35 of the lever 28. Before the machine is 120 started, however, the lever Z is pressed downwardly to bring the lower notch 7 into engagement with the detent-rod 10, but at this juncture the latch 38 will not have been carried far enough to engage the toe 35 of the lever 28. When this latter operation takes place the lever 125 Z is moved far enough to carry the latch 38 across the toe 35 of the lever 28 and the dog 30 will thereby be released from the quadrant 32. In this manner the dog 30 is released to bring the winding-mandrel B or 130

the package thereon down against the surface of the drive-roll D, and after the latch 38 swings into the position shown in Fig. 2, the dog is freed again to allow it to be re-engaged with its quadrant 32. The purpose of this arrangement is explained more fully in connection with the method of operation of the complete machine.

Referring now to Figs. 1, 2 and 6, at the front of the machine is a shelf-like frame or apron A on which are mounted several sets of tension-devices Y. These latter may be of any preferred type, and as here shown comprise three pairs of tension-plates or grids 45 arranged in opposed relation to adapt them to press against the yarns y drawing between their alternating bars. Extending across the frame A at the rear of the tension-devices is a rod 46, see Figs. 2 and 6, pivoted in bearings 47 and 48 and bent into U-shape at one end to form the extension 49, arranged parallel with its main portion 46. The free ends of the rods 46 and 49 are connected by an arm 50 which completes its rectangular form and provides a loop-like frame adapted to rock in its bearings 47 and 48. Pivoted on the rear rod 46 are a series of breakage levers or drop-wires 51, 51, arranged in alignment with the several tension-devices Y, see Fig. 6. Each drop-wire 51 is formed at its end with a helical coil 52 surrounding the rod 46 to support it pivotally thereon. From the end of the coil 52 the wire extends outwardly through a slotted opening 53 in the frame A which acts to restrain it from lateral movement in relation to its appropriate tension-device Y. At their forward ends the drop-wires 51 are bent at right-angles to form the parallel, horizontal cross-bars 54, 54, across which the yarns draw from the tension-devices Y in leading to the thread-guide G. As shown in Fig. 2 the yarns y lead outwardly from the tension-devices to form a relative sharp bend as they draw across the bars 54, 55, and thence lead back over a guide-rod 56 to the slot y' in the thread-guide G. The guide-rod 56 extends horizontally across the front of the frame F and is supported at one end by its bent portion 57 held in a bearing 58 by the set-screw 59. In some cases the yarns may lead up from the tension-devices Y to rolls or guide-pulleys, supported above the machine, and thence back in under the guide-rod 56 to the thread-guide G. This arrangement, however, being familiar to those skilled in the art, is not herein illustrated.

Referring still to Figs. 2 and 6, during the operation of the machine the drop-wires 51 are supported by the yarns y in raised position bearing against the forward cross-bar 49 of the double frame 46—49. The end arm 50 of said frame is formed with an extension 60 which bears against an adjust-

ing screw 61 held in the front of the frame A, see Fig. 2. A relatively light coiled spring 62 is hooked through a hole 63 in the arm 50 and anchored at its lower end to a staple 64 held in a lug 65 on the frame A. The spring 62 holds the extension 60 of the arm 50 normally bearing against the adjusting-screw 61, but allows for a slight lifting of the frame-rod 46 under abnormal resistance to the draft of the yarn which tends to swing the drop-wires upwardly. The mean positions of the drop-wires 51 may be regulated as required for different conditions of the winding by adjusting the screw 61 to alter the angle of the frame 46—49. Extending horizontally across the frame A beneath the drop-wires 51 is a wire-bail 66 having its ends bent at right-angles to its main portion and coiled around the wire 46 at 67 and 68. Projecting rearwardly from the end coil 68 is an arm 69 bent outwardly at 70 and formed with a hook 71 at its extremity, see Fig. 2. Suspended from the hook 71 is a link 72 having its lower end 73 hooked through the side of the knock-off lever 22. It will be understood that the weight of any one of the drop-wires 51, upon its release by the yarn y, is sufficient to tilt the bail 66 downwardly to raise its arm 69 and thereby lift the forward end of the knock-off lever 22. This action causes the rearward end of the lever 22 to be depressed to bring its cross-bar 25 into the range of the teeth of the ratchet 26 as before explained.

Extending across the top of the frame F in front of the drive-roll D is a sheet-metal cover or guard 75 which incloses the thread-guide G and protects it from dust and lint or contact with the operator's hands. The cover 75 is supported on a flange or ledge 76 on the tension-frame A and secured thereto by the screws 77. At its top are side-ears 78, 78 for supporting a horizontal cross-rod 79 on which is hinged the thread-bail or lifter 80, see Fig. 5. The bail 80 is preferably constructed in the form of a flat, sheet-metal plate having its inner edge folded over to present a smooth surface to the yarn. An ear 81 is turned down from its side and into this is hooked a wire link 82, see Fig. 3. The link 82 is connected by a turnbuckle 83 at its lower end to an extension 84 hooked into the arm 85 of a lever 86. The lever 86 is pivoted on the cross-rod r', which extends across the interior of the frame F, as previously described, and is formed with a forwardly extending arm 87 which reaches through an opening 88 in the front of the frame F. On its arm 85 is a cylindrical stud or projection 89 which engages the slot 21 in the forked end 20 of the slide-rod 16. When the rod 16 is slid rearwardly, through the action of the ratchet 26 on the knock-off

100

105

110

115

120

125

130

lever 22, its cam-slot 19 engaging the pin 18 will cause its forward end to be raised slightly. This action causes its fork 20 to rock the lever 86 whereby to tilt the thread-bail 80 upwardly through its connection by the link 82. In this manner the edge of the bail 80 is caused to lift the yarns y out from the slot g' in the thread-guide G, as shown in Fig. 3, the arm 87 acting as a stop to bear against the bottom of the opening 88 in the front of the frame F to limit its movement. The method of operation of the complete machine is as follows:

To prepare the machine for winding, the wooden cop-tube or mandrel B is applied to the end of the spindle V, with the key v' on the flange v engaged with its cross-slot b , see Fig. 1, and the other spindle V' is then inserted in its bore b' at the opposite end by manipulating the lever J. The yarns y are then led up from their source of supply, not here shown, but generally arranged below, and inserted between the bars of the tension-grids Y. As shown in Figs. 1 and 6 the machine is fitted with three separate tension-devices to adapt it for "doubling" or winding the yarns in multiple but a greater or less number of tensions could be used if desired. From the tension-devices Y the yarns are led up across the bars 54 and 55 of the drop-wires 51, and thence back over the guide-rod 56 and across the top of the thread-bail 80, see Fig. 2. It will be understood that the drive-roll D and cam C are driven continuously from the main drive-shaft of the machine which receives its motion from any suitable source of power, not here shown. The winding-mandrel B, however, is held out of contact with the drive-roll D, until the winding is to be started, with the brake-disk M bearing against the brake-shoe n as illustrated in Fig. 3. This relation of the mechanism is maintained by the action of the lever Z under the influence of its spring I when the detent-rod 10 is released from the notch 7 in its sector 6. The spring I tends to swing the lever Z in the direction opposite to that indicated by the arrow x' , Fig. 3, and the arm or link Q is thus caused to hold the forward end of the frame U raised with the mandrel B clear of the drive-roll D. It will be understood, of course, that the brake-arm N remains in fixed position in relation to the drive-roll D due to the binding action of its dog 30 in the groove 31 of the quadrant 32 which prevents it from moving downwardly.

Before starting the machine to wind the cop or package the operator places the fingers under the extension Z' on the frame-arm T and presses down on the end z' of the lever Z with his thumb. This causes the lever Z to be rocked in the direction indicated by the arrow x' , thereby bringing the notch 8 in its sector 6 into alinement with

the pointed end 9 of the detent-rod 10. The spring 27 will then act on the lever 13 to slide the rod 10 to engage its end with the notch 8 and meanwhile the frame U will have been lowered slightly in relation to the 70 brake-arm N so that the disk M is clear of the brake-shoe n . The release of the spindle brake-disk M from the shoe n allows the mandrel B to be turned on its bearings so that the ends of the yarns y can be secured 75 thereto more conveniently and wound on its surface to straighten their course from the tensions. This first movement of the lever Z also brings the latch 38 on its lower arm 4 into position adjacent the beveled end 37 of the toe 35 of the lever 28. Now, after the mandrel B has been rotated by hand to draw the yarns y taut, its surface is brought down into contact with the drive-roll D to start the winding in the following described manner: The operator presses on the end z' of the lever Z to depress it still farther and this causes its sector 6 to be rocked to bring the lower notch 7 into position to be engaged by the detent-rod 10. This last movement 80 of the lever Z will wipe the end 42 of the latch 38 across the bevel 37 on the toe 35 of the lever 28 to rock the latter to release the dog 30. With the dog 30 removed from binding engagement with the sector 32 the frame 85 U can then be lowered to carry the cop-tube B against the drive-roll D. As soon as the mandrel B has thus been brought into driving contact with the roll D the hand-lever Z may be released and it will remain locked 90 in the position shown in Fig. 2 by the engagement of the detent-rod 10 with its notch 7. With the lever Z thus held from movement under the tension of its spring I, it 95 will act through the arm Q to lock the frame U in fixed relation to the brake-lever N, with the brake-shoe n free from the disk M, and the two members are thus adapted to swing upwardly on their pivot-rod u as one part. Downward movement of the frame U and 100 arm N, however, will be prevented by the action of the dog 30 on the fixed sector 32. 105

With the parts of the machine adjusted to the position as just described and shown in Fig. 2, the drive-roll D will rotate the mandrel B through frictional contact of their peripheral surfaces and the cam C will reciprocate the thread-guide G back and forth longitudinally thereof. Referring to Fig. 3, it will be observed that when the winding-mandrel B is maintained away from the drive-roll to arrest its rotation, the stopping-mechanism of the machine is in such position that the thread-bail 80 will be raised on its pivot to hold the yarns y above and out of 110 range of the thread-guide G. When, however, the lever Z is operated to allow for placing the mandrel B in contact with the drive-roll D the thread-bail 80 will assume 115 its horizontal position as shown in Fig. 2, the 120 125 130

operation of this part of the mechanism being more fully explained later. Referring now to Fig. 5, it is to be noted that the upper portion g of the thread-guide G is shaped somewhat like an arrow-head with its sides sloping outwardly from the slot g' . As before stated, the thread-guide G is reciprocated continuously and hence as the winding-mandrel B is brought down against the roll D , after the thread-bail 80 has been depressed, the guide will ride in under the yarns y and pick them up to seat them in the slot g' . In this way the guide G is threaded automatically as soon as the mandrel B starts to rotate under the action of the drive-roll D .

As the machine continues to operate in the manner above described, the yarn will be laid on the tube B in crossed coils or helices which form layers to build up the cylindrical mass of the cop or package. As the winding increases in diameter with the addition of the successive layers it forces the mandrel or tube B upwardly away from the drive-roll D while the frame U swings on its pivot u to allow for this recession. The brake-lever N being locked in relation to the frame U is therefore caused to move with it and meanwhile the dog 30 acts on the quadrant 32 to prevent a return movement of the frame. Through this arrangement the frame U and the winding-mandrel B are prevented from vibrating or jumping up and down from the effect of irregularities or inequalities on the surface of the winding, and therefore a smoother action of the parts is secured tending to improve the character of the package. It is also called to attention that with the parts set for the winding operation, as shown in Fig. 2, the axis of the pin 17 which connects the slide-bar 16 with the lever 13 is coincident with the axis of the rod u on which the frame U and brake-lever N pivot. Therefore, as the frame U and lever N swing upwardly with the growth of the cop, there will be no tendency to displace the lever 13 to disturb the operative relation of the rod 10 and bar 16 .

The method of operation of the automatic stopping-mechanism of the machine is as follows: When any one of the yarns y becomes broken or its supply exhausted it will allow the outer end of its respective drop-wire 51 to fall and this action will cause the bail 66 , Figs. 3 and 6, to be tilted downwardly on its pivot 46 . The arm 69 of the bail 66 will thereby be raised to lift the outer end of the knock-off lever 22 , whereby to depress its rearward end and carry the crossbar 25 into position to be engaged by the teeth of the ratchet 26 . The ratchet 26 is rotated continuously with the cam-driving wheel W and during its engagement with the end of the lever 22 it will act to slide the bar 16 in the direction indicated by the arrow x ,

Fig. 3. The bar 16 will thereby be caused to rock the lever 13 to slide the detent-rod 10 to withdraw its end from engagement with the notch 7 in the sector 6 of the lever Z . The lever Z is thus unlocked to allow it to move under the action of its spring I to carry it into the position as illustrated in Fig. 3. As the lever Z rocks back in the direction opposite to that indicated by the arrow x' , Fig. 3, it will swing the arm Q on its pivot q to cause it to act as a toggle connection to raise the frame U in relation to the brake-lever N , see also Fig. 2. As before explained the arm N is held from downward movement by the dog 30 and hence the frame U must be raised relatively thereto, it being also called to notice that as the lever Z is rocked to effect this action the latch 38 will have no operative effect as it passes across the toe 35 of the lever 28 . That is to say, as the lower arm 4 of the lever Z swings to the left, as viewed in Fig. 3, the latch 38 will be free to tilt upwardly so that it will not bear forcibly against the toe 35 . For this reason the lever 28 will still remain active under the effect of its spring 27 and hence the dog 30 will not be released from binding engagement with the quadrant 32 .

As the frame U is raised to lift the surface of the cop away from the drive-roll D the brake-disk M will be carried against the shoe n and the momentum of the cop will thereby be checked to quickly arrest its rotation. Meanwhile, as the slide-bar 16 is slid in the direction indicated by the arrow x , Fig. 3, to effect this release of the stopping-means as above explained, its forward end will be raised slightly as its slot 19 rides along the fixed pin 18 . Through this action the lever 86 engaged by the forked end of the bar 16 will be rocked to raise the link 82 connected therewith, and in this manner the thread-bail 80 is tilted upwardly as shown in Fig. 3. As the bail 80 is thus raised against the yarns y it will lift them out from the slot g' in the thread-guide G and hence the guide as it continues to reciprocate will have no effect to traverse the yarns. In this manner the guide is prevented from abrading or cutting the yarns while the cop is at rest and they may also be manipulated more conveniently in piecing up the ends. It should perhaps be explained that the purpose of the lug 39 on the lower end of the lever Z is to provide for releasing the dog 30 after the parts have been locked in operative relation. That is to say, if the lever Z is first pressed down to an extent sufficient to lock it with the detent-rod 10 engaging its notch 7 , before the cop is brought into contact with the drive-roll D , by rocking it to a slightly greater extent its lug 39 will engage the bevel 37 on the toe 35 of the lever 28 to release the dog 30 . In other words, it is not absolutely

necessary to make sure that the cop is brought against the drive-roll when the latch 38 acts on the lever 28. This arrangement provides for a more convenient manual control of the dog 30 in whatever position the parts may be set and also allows for the movement of the frame U even after the machine has been started to operate. It is also called to attention that after the knock-off lever 22 has been operated on by the ratchet 26 it will be carried to a position with its lower web-portion above the edge of the ratchet. For this reason the teeth of the ratchet will simply ride against the under side of the lever to hold its rearward end raised with the cross-bar 25 out of their range. This prevents the ratchet from causing the lever 22 to vibrate or chatter against its teeth after the stopping of the machine. In starting the mechanism to wind again, after repairing a broken yarn or replenishing the supply, the same sequence of operations is performed as at first explained.

It will be observed that my improved stopping-devices provide for a quick, positive arrest of the winding upon the breakage or exhaustion of the yarn, and if occasion requires, the stopping may be effected manually by simply lifting up on the end of the knock-off lever 22. The cop is brought to rest almost instantly by the action of the brake-mechanism, and furthermore the action of the thread-guide on the yarn is immediately discontinued to prevent injury of the material and to provide for more convenient piecing up. In addition the starting-means is so arranged as to allow for release of the brake to permit the cop to be manually rotated to find a broken end, or to take up the slack after the end has been repaired, and in this way the operation of the whole machine is facilitated and rendered more convenient.

Various modifications might be made in the form and construction of the parts of my improved device without departing from the spirit or scope of the invention; therefore, without limiting myself to the exact embodiment shown and described, what I claim is:—

1. In a winding machine, the combination with the traversing thread-guide and rotating drive-roll, of a pivoted frame for supporting the cop in contact with the drive-roll, an arm pivoted on the axis of the frame and movable therewith as the axis of the cop recedes from the drive-roll during the growth in the winding, means to connect the frame and arm to move together, means to dog the arm to prevent the frame from moving toward the drive-roll, and stopping-means to move the frame in relation to the arm to withdraw the cop from contact with the drive-roll.

2. In a winding machine, the combination

with the traversing thread-guide and rotating drive-roll, of a pivoted frame for supporting the cop in contact with the drive-roll while allowing its axis to recede therefrom with the growth in the winding, a stop-member pivoted on the same axis with the frame to adapt it to move therewith, detent-means for connecting the frame and stop-member to move together, means to release the detent-means, and means acting between the stop-member and frame to displace the latter in relation to the former to remove the cop from contact with the drive-roll to arrest its rotation.

3. In a winding machine, the combination with the rotating drive-roll and reciprocating thread-guide, of a winding-mandrel on which the cop is wound through contact with the drive-roll, a frame for supporting the mandrel to allow it to recede from the drive-roll with the growth in the winding, a stop-member movable from and with said frame, means to connect said frame and stop-member to move together, means to dog the stop-member during its movement with the frame to prevent retrogressive movement thereof, and means to move the frame in relation to the stop-member while the latter is held by its dogging-means to withdraw the cop from contact with the drive-roll.

4. In a winding machine, the combination with the reciprocating thread-guide and rotating drive-roll, of a swinging frame for supporting the cop with its surface in contact with the drive-roll, an arm adapted to swing with the cop-supporting frame, means connecting the arm and frame to move together as the axis of the cop recedes from the drive-roll during the increase in diameter of the winding, means to prevent the arm from moving in the opposite direction toward the drive-roll, and stopping-means for moving the frame in relation to the arm to withdraw the cop from contact with the drive-roll to arrest its rotation upon the breaking or exhaustion of the yarn being wound.

5. In a winding machine, the combination with the reciprocating thread-guide and rotating drive-roll, of a movable frame for supporting the cop in contact with the drive-roll while allowing its axis to recede therefrom with the growth in the winding, a stop-member movable with the frame, an arm pivoted on the stop-member, a lever pivoted on the frame and connected to the arm, detent-means for locking the lever to maintain the stop-member and frame in fixed relation, and means to operate the lever upon the release of the detent-means to move the frame in relation to the stop-member to withdraw the cop from contact with the drive-roll.

6. In a winding machine, the combination with the reciprocating thread-guide and ro-

- 8
- tating drive-roll, of a movable frame for supporting the cop in contact with the drive-roll while allowing its axis to recede therefrom, a stop-member movable with the frame, an arm pivoted on the stop-member, a lever pivoted on the frame and connected with the arm, a spring to rock the lever, detent-means to lock the lever to hold the frame and stop-member in fixed relation 5 during the winding, and automatically operated stopping-devices for releasing the detent-means to allow the lever to rock under the action of its spring to move the frame in relation to the stop-member to withdraw 10 the cop from contact with the drive-roll.
7. In a winding machine, the combination with the reciprocating thread-guide and rotating drive-roll, of a pivoted frame for supporting the cop to adapt it to be driven from the roll, a stop-member pivoted on the axis of the frame to move therewith, an arm pivoted on said stop-member, a hand-lever pivoted on the frame and connected with the arm on the stop-member, a spring for rocking 20 the hand-lever, a detent-member engageable with the hand-lever to restrain it from rocking to hold the stop-member and frame in fixed relation, and stopping-devices actuated by the failure of the supply-yarns 25 to release the detent-means to allow the hand-lever to rock to displace the frame in relation to the stop-member to withdraw the cop from contact with the drive-roll.
8. In a winding machine, the combination with the reciprocating thread-guide and rotating drive-roll, of a winding-mandrel on which the cop is wound through contact with the drive-roll, a brake-disk rotatable with the mandrel, a frame for supporting 30 the mandrel to adapt it to recede from the drive-roll with the growth in the winding, a brake-lever movable with the frame and carrying a brake-shoe, an arm pivoted to the brake-lever, a hand-lever pivoted on the frame and connected with the arm on the brake-lever, a spring to rock said hand-lever, a detent to maintain said hand-lever locked against the action of the spring, and stopping-devices to release the detent to allow 35 the hand-lever to rock to move the frame in relation to the brake-lever to withdraw the cop from contact with the drive-roll and to concurrently carry the brake-disk into engagement with the brake-shoe.
9. In a winding machine, the combination with the reciprocating thread-guide and rotating drive-roll, of a pivoted frame for supporting the cop in contact with the drive-roll, a stop-member pivoted on the axis of the frame to adapt it to move therewith as the axis of the cop recedes from the drive-roll with the growth in the winding, dogging-means on the stop-member to prevent it from moving in the opposite direction toward the drive-roll, a stopping-lever 40 45 50 55 60 65

pivoted on the cop-frame, an arm connecting said stopping-lever with the stop-member, a spring to rock the stopping-lever to raise the cop-frame in relation to the stop-member to lift the cop off from the drive-roll, a 70 detent to prevent the action of the stopping-lever, and automatically-operated means for releasing the detent upon the breakage or exhaustion of the yarn being wound.

10. In a winding machine, the combination with the reciprocating thread-guide and rotating drive-roll, of a frame for supporting the cop in contact with the drive-roll while allowing its axis to recede therefrom with the growth in the winding, a 80 stop-member movable with the frame away from the drive-roll, dogging-means for preventing the stop-member from moving toward the drive-roll, a stopping-lever, means for operating the stopping-lever to move the 85 frame in relation to the stop-member to withdraw the cop from contact with the drive-roll, detent-means for maintaining the stopping-lever inactive during the winding, and means operative to release the dogging 90 means to allow the cop to be placed in contact with the drive-roll when the stopping-lever is operated manually to engage it with its detent-means.

11. In a winding machine, the combination with the reciprocating thread-guide and rotating drive-roll, of a swinging frame for supporting the cop in contact with the drive-roll while allowing its axis to recede therefrom, a stop-member connected to move with the frame as the cop increases in diameter, dogging-means for preventing the stop-member and frame from moving toward the drive-roll, a stopping-lever connecting the frame and stop-member, a spring for rocking 100 the stopping-lever to displace the frame in relation to the stop-member to withdraw the cop from contact with the drive-roll, detent-means to hold the stopping-lever normally inactive, and means operated when the stopping-lever is moved manually 105 against the action of its spring to release the dogging-means to allow the cop to be carried into contact with the drive-roll.

12. In a winding machine, the combination with the reciprocating thread-guide and rotating drive-roll, of a winding-mandrel on which the cop is wound through contact with the drive-roll, a brake-disk rotatable with the mandrel, a frame for supporting the mandrel to adapt it to recede from the drive-roll, a brake-arm connected to move with the frame as the cop increases in diameter, dogging-means connected with the brake-arm to prevent the frame from moving toward the drive-roll, a stopping-lever connected with the frame and brake-arm, a spring to operate the stopping-lever to move the frame in relation to the brake-arm to withdraw the cop from contact with 110 115 120 125 130

the drive-roll and carry the brake-disk into engagement with the brake-arm, detent-means for locking the stopping-lever against movement by its spring, and means operative to release the dogging-means for the brake-arm and frame when the stopping-lever is carried into engagement with its detent-means.

13. In a winding machine, the combination with the reciprocating thread-guide and rotating drive-roll, of a cop-supporting frame pivoted to swing away from the drive-roll, a rotatable winding-mandrel carried by said frame, a brake-disk rotatable with the mandrel, a brake-arm pivoted to swing with the cop-frame, dogging-means acting on the brake-arm to prevent the cop-frame from swinging toward the drive-roll, a stopping-lever connecting the cop-frame and brake-arm to move together, means to operate the stopping-lever to raise the cop-frame in relation to the brake-arm to lift the cop off from the drive-roll and carry the brake-disk into contact with the brake-arm, detent-means for withholding the stopping-lever from action, and means whereby the stopping-lever may be engaged with the detent-means in one position to release the brake-disk from the brake-arm and in another position to release the dogging-means to allow the cop to be placed in contact with the drive-roll.

14. In a winding machine, the combination with the reciprocating thread-guide and rotating drive-roll, of a cop-supporting frame pivoted to swing away from the drive-roll, a rotatable winding-mandrel carried by said frame, a brake-disk rotatable with the mandrel, a brake-arm pivoted to swing with the cop-frame as the mandrel recedes from the drive-roll during the growth of the cop, dogging-means for controlling the movement of the brake-arm to prevent the cop-frame from swinging toward the drive-roll, a stopping-lever pivoted on the cop-frame and formed with a notched sector, means connecting the stopping-lever to move the cop-frame in relation to the brake-arm, a spring to operate the stopping-lever to remove the cop from contact with the drive-roll and carry the brake-disk into engagement with the brake-arm, a detent-member engageable with one notch in the stopping-lever to hold the brake-disk released from the brake-arm, and means operated by the stopping-lever to release the dogging-means for the brake-lever when its other notch is carried into engagement with the detent-member.

15. In a winding machine, the combination with the reciprocating thread-guide and rotating drive-roll, of a frame adapted to swing away from the drive-roll, a winding-mandrel carried by said frame, a brake-disk rotatable with the mandrel, a brake-arm

movable with the cop-frame away from the drive-roll, a dog carried by said brake-arm, a fixed quadrant engaged by the dog to prevent movement of the brake-arm and cop-frame toward the drive-roll, a lever for 70 operating the dog, a spring for operating the dog-lever, a stopping-lever for displacing the frame in relation to the brake-arm to engage the brake-disk therewith, a detent for maintaining the stopping-lever normally inoperative, and a latch for operating the dogging-lever to release the dog when the stopping-lever is engaged with its detent. 75

16. In a winding machine, the combination with the reciprocating thread-guide and rotating drive-roll, of a movable frame for supporting the cop in contact with the drive-roll while allowing its axis to recede therefrom, a stop-member movable 80 with the frame away from the drive-roll, a stopping-lever carried by the frame and connected with the stop-member, means to operate the stopping-lever to displace the frame with respect to the stop-member to 85 withdraw the cop from contact with the drive-roll, a detent-member for maintaining the stopping-lever normally inactive, a knock-off lever for releasing the detent-member, a ratchet for operating the knock-off lever, and drop-wires controlled by the 90 yarns being wound and releasable thereby to cause the knock-off lever to engage with the ratchet. 95

17. In a winding machine, the combination with the reciprocating thread-guide and rotating drive-roll, of a swinging frame for supporting the cop in contact with the drive-roll, an arm mounted to swing with the frame as the cop increases in diameter, 100 a stopping-lever for displacing the frame in relation to the arm to lift the cop away from the drive-roll, a detent-rod slidably mounted on the frame to engage the stopping-lever to withhold it from action, a bell- 105 crank-lever pivoted on the frame and connected to slide the detent-rod, a slide-bar connected to operate the bell-crank-lever, and means controlled by the yarn being wound to move the slide-bar to release the detent- 110 rod. 115

18. In a winding machine, the combination with the reciprocating thread-guide and rotating drive-roll, of a movable frame for supporting the cop in contact with the 120 drive-roll, an arm movable with the frame as the cop increases in diameter, stopping-means for displacing the frame with respect to the arm to withdraw the cop from contact with the drive-roll, a detent-member for 125 maintaining the stopping-means inactive, a bell-crank-lever for withdrawing the detent-member, a slide-bar for operating the bell-crank-lever, a ratchet-wheel, a knock-off lever pivoted on the slide-bar to adapt it to 130

engage with the ratchet-wheel, and means for moving the knock-off lever into engagement with the ratchet upon the failure of the yarn being wound.

- 5 19. In a winding machine, the combination with a continuously reciprocating thread-guide for traversing the yarn on the cop, of a thread-bail adapted to be shifted in position in relation to the thread-guide
- 10 to lift the yarns out therefrom, a rotating drive-roll, a swinging frame for supporting the cop to be rotated from the drive-roll, stopping-means for moving the frame to withdraw the cop from contact with the
- 15 drive-roll, detent-means to maintain the stopping-means normally inoperative, a longitudinally-slidable bar for releasing the detent-means, a rotatable ratchet-wheel for sliding the bar, a cam for raising the bar
- 20 during its sliding movement, and means operated from the raising of the bar to shift

the thread-bail as the cop is withdrawn from contact with the drive-roll.

20. In a winding machine, the combination with a continuously reciprocated 25 thread-guide for traversing the yarn on the cop, of a movable thread-bail arranged adjacent the path of traverse of the guide, a continuously rotated drive-roll, a frame for supporting the cop to be rotated from the 30 drive-roll, stopping-means to move the frame to withdraw the cop from contact with the drive-roll, detent-means to hold the stopping-means normally inoperative, a longitudinally-slidable bar for releasing the 35 detent-means, means to slide the bar, means to raise one end of the bar laterally during its sliding movement and a link connected with the bar to raise the thread-bail to lift the yarn out of the thread-guide.

In testimony whereof I affix my signature,

EDWARD F. PARKS.
